HAIR CLIPPING AND SHAVING HEAD

Mathew Andis, Racine, Wis.

Application March 5, 1936, Serial No. 67,196

7 Claims. (Cl. 30—43)

My invention relates to improvements in shearing heads for hair clipping and shaving devices. While my invention may be embodied in manually operated devices, it is particularly adapted for embodiment in devices which are power driven and in which the vibratory cutter is reciprocated at high speed.

Objects of my invention are: to provide a shearing head adapted for arcuate bearing upon the scalp under sufficient pressure to compress the flesh and produce a concave groove in that portion of the scalp where the clipping or shaving operation is being performed; to provide means for placing the scalp under stretching tension in the zone where hair is being clipped; to provide a shearing head adapted for movement along a scalp in either of two directions or for reciprocatory movement, with equal shearing efficiency at each side of the center of the zone of contact; to provide extremely thin shear teeth for contact with the scalp, said teeth being arcuate and substantially unyielding by reason of the comparative strength inherent to the arch form; to provide means for connecting the arched shear teeth with each other along the crown of the arch for combing or hair straightening purposes and additional reinforcement of the thin shear teeth; to provide improved vibratory cutters for reciprocation along the concave or inner faces of the arched shear teeth; to provide means whereby hair may freely pass between end portions of the shear teeth without being blocked or prevented from such entry by the vibratory cutter; to provide an improved compressible vibratory cutter adapted to resiliently maintain pressure upon the shear teeth and take up wear; and in general, to provide shaving and clipping heads of small cross section and light weight adapted to be assembled with tubular handles containing driving mechanism, and which handles and driving mechanisms are of light weight and correspondingly small in cross section, whereby ease of manipulation and improved efficiency may be obtained.

In the drawing:

Figure 1 is an elevation of my improved clipper head associated with a tubular operating handle.

Figure 2 is a plan view of the shearing head and associated parts, with the upper half portion of the handle partially broken away, and with the non-vibratory shearing member shown partially in section on the plane of handle division.

Figure 3 is a fragmentary sectional view of

the shearing portion of the head in contact with the scalp during a hair clipping or shaving operation.

Figure 4 is a sectional view drawn to line 4—4 of Figure 2.

Figure 5 is a similar view showing a modification.

Figure 6 is a perspective view of the vibratory cutter bar with its control portion broken away.

Like parts are identified by the same reference characters throughout the several views.

In my former Patent No. 2,037,957, for Hair clipper and shaving clipper, granted April 21, 1936, on a companion application, Serial No. 581,634, filed by me December 17, 1931, I have 15 illustrated a tubular vibratory clipper mounted within a shear plate having forwardly projecting comb teeth, said shear plate being adapted for substantially flat bearing contact with the scalp. The invention herein disclosed embodies 20 features which may be regarded as partly divisional to those disclosed in Figure 4 of said former application, although the features common to the two applications are not claimed 25 in the former application.

In the improved shearing head herein disclosed, the body 10 of the non-vibratory shearing member will preferably have the form of an elongated bar, the rear face of which may be recessed as indicated at 11 in Figures 4 and 5. 30 Between the recesses, the rearwardly extending and preferably rectangular projections 12 provide convenient means for connecting the handle to the body 10. Preferably these projections 12 are provided with upwardly and downwardly extending studs 13 adapted to fit suitable sockets in the nose or forward end portion 14 of the respective halves of the handle, the handle being divided in a plane which includes the longitudinal center line of the shearing head. 35

It may be understood that any suitable driving mechanism, or even a driving motor, may be contained within the handle, it being common in the art to employ electromagnetic motors for such purposes. Any suitable driving means may 40 be employed, and further illustration and description is deemed unnecessary.

The shear bar 10 is provided with a longitudinally extending tubular passage within which a vibratory cylindrical cutter may be mounted. 50 The forward or working portion of the shear bar 10 has a quadrant, preferably both the upper and lower quadrants, arcuately slotted to provide curved shear teeth 16 and 17, the convergent ends of which teeth are connected by a hair 55

lifting or razor web 18. The rear ends of the shear teeth 16 and 17 are materially thicker than the forward end portions adjacent the web 18, the outer surfaces of the teeth being formed in the arc of a circle which is not strictly concentric with said tubular passage in that it has its axis at the rear of the axis of said tubular passage. The increased thickness of the outer or cutter ends of the teeth 16, or 16 and 17, is sufficient to give the teeth adequate strength notwithstanding the fact that the forward or shearing end portions of the teeth are made approximately as thin as an ordinary razor blade adjacent its cutting edge.

Owing to the arched curvature of the teeth 16, 17, and their connection with the web 18 at their working ends, with progressively increasing thickness to their points of connection with the rear portion of the body 10, the portions of the teeth which bear upon the skin may be made exceedingly thin without impairing their resistance to strains imposed by any ordinary working conditions.

The vibratory cutter bar is formed to fit the cylindrical bore in the shear bar. It has the form of a cylinder having oppositely disposed longitudinal channels 19 and 20 in its periphery between the front and rear portions 21 and 22 respectively. The portion 21 is also arcuately channeled to provide arcuate shearing teeth 23. Between the channels 19 and 20 the cutter bar is provided with slots 25 and 26 which extend inwardly from opposite ends to permit a limited degree of approach between the portions 21 and 22 when the cutter bar is subjected to compression. The cutter bar is composed of resilient material and is normally slightly larger in diameter than the bore in the shear bar which receives it. It is inserted while under compression and is thus biased for expanding pressure to hold the cutter teeth 23 in resilient pressure contact with the outer cutter teeth 16 and 17 and web 18 of the non-vibratory shear bar.

The channels 19 and 20 on opposite sides of the bar between the teeth 23 allow hair to freely enter the spaces between the non-vibratory shear teeth 16 and 17 along the portions in registry with these recesses 19 and 20. This overcomes a serious difficulty heretofore experienced in the use of shearing devices of the general type herein disclosed, due to the tendency of a rapidly vibrating cylindrical cutter bar to prevent hair from entering a cylindrical bore in a non-vibratory shear bar. In analogy to the comb teeth of an ordinary hair clipper, the rear portions of the shear teeth 16 and 17 may, for convenience of description, be designated as the combing portions.

It will be understood that when the tool is in operation it will be moved back and forth along the scalp or skin, and therefore hair entering the channels 19 and 20 may occupy positions perpendicular to the skin before the vibratory cutter comes in shearing relation thereto, since the hair has relatively longitudinal movement between the ends of the shearing teeth.

In Figure 5 the non-vibratory shearing member 10a with its recess 11a and coupling projections 12a may be similar in form to that shown in Figure 4, and similarly slotted to provide cutter teeth 35 and 36. The web 18 illustrated in Figure 4 may be omitted to allow hair to enter the tubular cavity 37 in the vibratory bar in the manner above described with reference to entry of hair in the channels 19 and 20.

The vibratory cutter bar 30 has teeth 31 and 32 and may have a comparatively thick integral rear portion, and the cutter bar may be fitted to the cylindrical cavity in the shear bar under compression, whereby it will be biased for expansion and hold its shearing teeth in firm contact with the shear teeth of the non-vibratory member.

It is not essential to my invention that hair lifting webs 18 should be employed in the form of construction shown in Figure 4, but the use of such webs is preferred for the reason that it is desirable that each hair should be perpendicular to the skin at the time of severance. Otherwise additional manipulation of the tool over the same portion of the skin may in some cases be found necessary or desirable.

In operation, the shearing members are reciprocated, preferably with a rocking motion, upon the surface of the skin and with sufficient pressure to compress the flesh and produce a concave depression in the skin. The skin is thus placed under tension throughout the shearing zone with a tendency to cause the hair to spring resiliently to a position perpendicular to the skin. I believe I am the first to provide a clipping mechanism in which such a tensioning of the skin is made possible, and in which the handle may be held substantially at right angles to the skin or rocked and reciprocated across a perpendicular plane while the cylindrically curved shearing member is pressed against the skin as above described.

This application is continuing or divisional in part to said companion application Serial No. 581,634. In said companion application I have illustrated but not claimed shear teeth having thin working portions and progressively thickening portions connecting the working portions with a shear plate or body, but neither the illustration nor the description is deemed sufficiently complete to serve as a foundation for generic claims to such teeth, and therefore a clarified disclosure is made in this application and certain combination claims formerly included in said former application, containing references to teeth of varying thickness in a plane normal to the working surfaces, have been cancelled.

I attach considerable importance to the fact that the shear teeth disclosed in this application are not only progressively thickened from the thin working portions in the direction of the body, but that the working portion, and preferably the entire tooth, is formed for skin tensioning purposes by compression along the center line of the bearing portion, whereby the work is done in a concave depression formed in the skin and flesh for such tensioning purposes.

In Figure 2 I have illustrated the cutter bar as provided with an actuating arm 50, which has a split head portion 51 socketed in the portion 22 of the cutter bar, whereby the latter may be vibrated or reciprocated in the shear bar bore. Since any suitable means for vibrating the cutter bar may be employed, the means illustrated may be assumed to be representative of any ordinary actuating means.

I claim:

1. In a mechanism of the described class, a cutter bar having cylindrically rounded front and rear portions and oppositely disposed longitudinally extending channels, the front portion being arcuately slotted to provide shearing teeth, and the material between said channels having slots extending inwardly from each end

of the bar in different planes and overlapping relation to each other to allow the front and rear portions to approach each other under compression.

5. 2. In a mechanism of the described class, a cutter bar having cylindrically rounded front and rear portions and oppositely disposed longitudinally extending channels, the front portion being arcuately slotted to provide shearing teeth, 5 and the material between said channels having slots extending inwardly from each end of the bar in different planes and overlapping relation to each other to allow the front and rear portions to approach each other under compression, 10 15 in combination with a tubular shear bar having a bore adapted to receive said cutter bar under compression and provided with a thin concentric portion arcuately slotted to provide shearing teeth.
- 20 3. In a mechanism of the described class, a cutter bar of generally T-shaped cross section having arcuate front and rear portions connected along their longitudinally extending centers by a relatively thin web adapted to yield resiliently 25 under pressure tending to force the front and rear portions toward each other, said front portion having its curved surface arcuately channeled to provide shearing teeth.

4. In a mechanism of the described class, a 30 cutter bar having longitudinally extending front and rear portions provided with arcuate outer surfaces and connected with each other by a resiliently yielding web portion, above and below which channel-like spaces are provided between 35 said front and rear portions.

5. In a mechanism of the described class, a cutter bar of a generally T-shaped cross section having a central longitudinally extending rela-

tively thin web composed of resilient material, having staggered slots extending inwardly from each end across the center of the web to facilitate forcing the front and rear portions toward each other under pressure, whereby said bar 5 may, by its own expansion, exert resilient pressure against the walls of a cylindrical bore in a cooperative shear bar.

6. The combination of a vibratory cutter bar 10 having a cylindrically curved working portion along one side, arcuately channeled to provide cutting teeth, said cutter bar also having an operating back portion connected with the concave inner face of its working portion along its longitudinal center line by a resiliently yielding web, 15 adapted to subject the entire surface of the working portion to substantially equal pressure upon a shear bar arcuately concentric with said working portion.

7. In a mechanism of the described class, a 20 hollow shear bar provided with a longitudinally extending opening in its periphery and having a thin working portion cylindrically curved and arcuately slotted to provide shearing teeth extending into said peripheral opening, in combination with a cutter bar having front and rear 25 portions conforming to the inner surfaces of the hollow shear bar, including those of said working portion, and a web spaced from the wall of the shear bar and its peripheral opening, said 30 web being of resilient material adapted to allow the front and rear portions to be forced toward each other under pressure when the cutter bar is inserted in the shear bar, said cutter bar having teeth in pressure contact with the shear 35 teeth of said working portion of the shear bar.

MATHEW ANDIS.
